HARVEY J. HARWOOD AND WILLIAM H. MICKLE, OF UTICA, NEW YORK, ASSIGNEES TO
HARVEY J. HARWOOD AND JOHN F. SEYMOUR, OF SAME PLACE.

Letters Patent No. 72,490, dated December 24, 1867.

IMPROVED MACHINE FOR THREADING SCREWS.

The Schedule referred to in these Letters Patent and making part of the same.

TO ALL WHOM IT MAY CONCERN:

Be it known that we, HARVEY J. HARWOOD and WILLIAM H. MICKLE, both of Utica, county of Oneida; and State of New York, have invented certain new and useful Improvements in Machinery for Making Wood-Screws; and we do hereby declare that the following is a full, clear, and exact description of the construction and operation thereof, reference being had to the annexed drawings, making a part of this specification, in which the figures are all reduced in size.

Figure 1 is a perspective view.

Figure 2 is a horizontal section, made on a plane with the upper surfaces of the dies A and B, fig. 1 showing a perspective of the double crank E and its connections.

Figure 3 is a horizontal section through, on the plane of the upper surface of L, fig. 1.

Figure 4 is a transverse section through, on a line between k and m, fig. 1.

Figure 5 is a longitudinal elevation of die A, figs. 1, 2, and 3.

Figure 6 is a sectional view of the guides k, l, and m, fig. 1, made lengthwise between dies A and B.

To enable others skilled in the art to make and use our invention, we will proceed to describe its construction and operation.

We construct our machine with dies, so formed as to make screws of the shape desired. The following is the form of die we prefer: in figs. 4 and 5, they have grooves cut on the faces that are toward each other, leaving the metal between the grooves in the form of threads, said threads to be of the size and shape of the space intended to be between two contiguous coils of the thread on the blank to be threaded, or of the size and shape of the space intended to be between two contiguous threads of the blank to be threaded. Said thread should form, with the edge of the die, an angle equal to the angle of the thread or threads intended for the blank, except the part that forms the point of the screw, (the point of the screw is formed on the raised part of the dies,) which part curves so as to increase said angle, thereby increasing the pitch of the screw at the point which enables its lips to more readily enter wood. The edge of the thread of the die, as viewed in a transverse section of the die, (fig. 4,) should be of the desired form of core for the intended screws (which is the same in Charles R. Gardner's die, patented August 12, 1856.) We make our dies where we form the lip or lips of the screws (commonly called the point of the screw) so deep as not to reduce the diameter of the screw in that portion. We commonly make it of its greatest diameter there, which is not the case with any other dies. We sometimes make the dies so as to form a screw tapered for one or two threads at the entering end. The dies A and B are channelled beyond the part which forms the point of the screw, to allow the refuse metal to escape. The dies A and B are each double dies, and can be made of one or more pieces each (figs. 4 and 5.)

We operate the dies A and B, figs. 1, 2, and 4, by a double crank, E, fig. 2, which is connected by pitmen C and D, and imparts a reciprocating movement to each die, and causes them to move in opposite directions, and each die to move the same distance, so when a blank is being formed into a screw, it rotates upon its own axis and does not travel. The same movements can be obtained with screws or racks and pinion. The guides k, l, and m, figs. 1, 2, 3, 4, and 6, are to hold the blank at right angles to the edge of the dies while it is being threaded. The guide m, fig. 1, is attached to the frame. The guides k and l are so attached that they can be moved to and from m. o is an arm of k, and n is an arm of l. o and n cover the blank while it is being threaded, so that when k is opened, it uncovers the place for the blank to enter between l and m; and when l is opened, it uncovers the place for the blank to enter between m and k. The guides k and l, fig. 1, are opened and shut by the pin or stud i, in die A, figs. 2 and 3, acting upon the cams or inclined planes on catches r and s, fig. 3. Catches r and s are connected to k and l. The pin or stud i enters the opening in r. Passing along the inclined plane, it raises r out of the notch in m; then it presses against the bottom of the opening in r, thereby crowding k back, (k being attached to r,) so, when A has completed its stroke in that direction, the guide k is far enough from m to allow the screw-head to fall through the opening between k and m, and while it is in said position, there are depressions opposite each other, on the faces of the dies A and B, large enough to allow the screw-head to pass between them. There is also an aperture in the bottom of the frame, under said depressions, and in line therewith, so that the screw can fall through the machine. At the same time, on the

other side of *m*, the opening between *m* and *l* being uncovered, a blank is inserted in said opening. Now the dies change their motion, and the pin or stud *i* presses against the cam *a*, and carries *r* and its appurtenances along, until the guide *k* reaches guide *m*, then the catch *r* is pressed into the notch in *m* by the pin *i* acting upon the cam *a* on *r*. At this time rib 5 on die A comes travelling back of catch *r*, and holds it down until pin or stud *i* returns. The pin or stud *i* travels along with A until *i* reaches catch *s*, when the same or a similar operation to that performed at catch *r* is repeated. The same or a similar operation is repeated each stroke. There are two slight depressions in die A, at 6 and 7, and one heavy depression at 8, figs. 2 and 5. B has a slight depression opposite depression 8 on A, figs. 2 and 5, and heavy depressions opposite 6 and 7 on A. When the dies A and B are at the end of their movements in either direction, the large depression, 8, in the centre of die A, is opposite one of the large depressions in the ends of B at the same time the small depression in the centre of die B is opposite one of the small depressions in the ends of die A. And while the dies are in this position, the blank to be threaded is inserted in the opening formed by the small depressions. Then, as the crank E is turned one-half of a revolution, the blank is rotated on its own axis, and threaded by the dies A and B. While being threaded, the blank is held at right angles with the face of the dies by the guides *k*, *l*, and *m*, figs. 1 and 6.

We do not broadly claim reciprocating dies, but

What we do claim as our invention, and desire to secure by Letters Patent, is—

1. We claim the combination of the reciprocating dies A and B, and guides *k*, *l*, and *m*.
2. We claim the construction of the curved part of the threads on the die that forms the point of the screw of increased pitch, as described.
3. We claim the channels *v v v*, in the dies A and B, that extend beyond the part of the die that forms the point of the screw.
4. We claim the general arrangement of the parts whereby the dies are enabled to operate upon two screws during each revolution of the crank E.
5. We claim the opening and closing of the guides *k*, *l*, and *m*, in the manner and by means substantially as described.
6. We claim the guides *k* and *l*, and their arms *o* and *n*, arranged in the manner and for the purpose described.

H. J. HARWOOD,
WILLIAM H. MICKLE.
